UNITED STATES PATENT OFFICE.

GEORGE E. MARLATT, OF PASADENA, CALIFORNIA.

TYPOGRAPHICAL ASSEMBLER.

Application filed October 25, 1927. Serial No. 228,620.

This invention is concerned primarily with shifting the duplex or upper assembler rail of linotype and such machines by finger-key means, as an improvement over the usual 5 method of shifting the rail in order to cause selected matrices to be supported at an upper or lower level in the assembler. The chief advantage attained is that individual matrices may be caused to lodge at a predetermined 10 level as they enter the assembler, and this without reading the matrices or handling them, and without opening the assembler gate.

An object in view is to combine in one 15 structure all the features essential to a practical device, and to this end I provide means whereby the thickness of the first incoming matrix destined for the lower assembler rail will determine and regulate the initial movement of the upper rail to non-supporting and 20 non-interfering position; means which does not require observance of the matrices when a shift is made from one to another rail or level; a construction sufficiently like the common 25 construction so that its use is natural and an operator will not be inconvenienced when changing to or from a machine equipped with the improvement; a device readily applicable to outstanding machines; a construction 30 which does not complicate or add to the manufacturing cost of machines embodying the improvement; means controlled by keys conveniently located; means which will not interfere with assembling the spacers or so-called 35 spacebands; means which will not interfere with transferring the assembled lines to and through the usual intermediate channel as the lines move toward casting position. Minor and contributing improvements 40 which would be useful apart from the primary purpose are also provided and the advantages thereof are set forth hereinafter as the description progresses.

In the following description I will outline 45 in detail that form of embodiment of the invention which I have selected for illustration in the drawings accompanying and forming part of the present specification, this form being primarily provided to enable those skilled in the art to practice the invention. It will of course be clear that I am not restricted to such disclosure, but may depart therefrom in any way within the scope of the invention defined by the claims following the description. The application of my 50 invention to assemblers of the elevator type

is merely illustrative, and the operative connections would necessarily be varied if the invention were applied to other kinds of assemblers.

The common method of assembling duplex character matrices involves frequent opening and closing of the assembler gate and direct manual handling of the matrices in order to place selected matrices on a selected rail. 60 The index characters on the matrices are read only with difficulty when the matrices are in the assembler, and as a consequence the assembled line may be sent to the casting station with words or portions thereof at a 65 level other than the one intended. As a typical example may be mentioned a line of capitals and small capitals wherein the initial letters of principal words must be lowered manually one at a time from upper to lower 70 rail. If the method employed in such a case is that of opening the assembler gate each time a capital letter is collected in the assembler, this in itself is tedious and annoying; and if the complete line is first assembled, then the words must be read to determine 75 which one thereof carry the capital initial letter; and by either method the matrices and spacers are liable to become disordered and jammed while the assembler gate 80 is open, for the matrix to be lowered or raised must first be turned or tilted in order that its lower lug may clear and pass the upper supporting rail. Substantially the same 85 annoyances occur incident to manipulating the matrices in mixed lines of roman and italic, roman and boldface type, or in quad or leader lines. In the case of quads and leaders, the leader matrices serve for quads if assembled 90 on the upper rail, and the quads serve for 95 leaders if assembled on the upper rail; and frequently both must be employed in the same quad or leader line since there are not enough of either to fill out a long line in the assembler.

100 In the accompanying drawings, in which similar reference characters designate similar parts throughout the several views,

Fig. 1 is a front elevation showing the relation of the improved assembler to the keyboard, matrix delivery throat and line delivery channel of a typographical machine of the linotype class;

Fig. 2 is a perspective view showing the 105 assembling elevator in full lines in lowered or matrix-receiving position and in dotted lines in raised or line-delivering position, dis-

closing the movable matrix-supporting rails of the present invention as having been shifted during movement of the assembler from lowered to raised position;

5 Fig. 3 is a detail;

Fig. 4 is a perspective view similar to Fig. 2 but showing the movable matrix-supporting rails shifted to matrix-receiving position;

Fig. 5 is an elevation of the matrix-receiving end of the assembler;

Fig. 14 is a rear view perspective of the front wall of the assembler.

25 In common practice only one upper or duplex assembler rail has been provided, corresponding in position to the front rail 1 of this invention. For present purposes I prefer to provide an opposite rail 2. Nevertheless, in a cheapened construction, either one of these rails will serve the purpose in view just as a single rail has heretofore served for supporting the matrices X in raised position; or, in connection with three-character

35 matrices, the movable rails may occupy different levels and the rear rail could serve for supporting matrices at the third level. In order that the front rail 1 may be readily shifted both longitudinally and transversely

40 by means of the distant control to be described, I mount this rail 1 in a floating manner between the rail cap A and the front wall B of the assembler. To this end the cap A is spaced from the wall B by means of a post

45 3 at the inner or receiving end of the assembler, and at the outer end by means of a spacing plate 4. I provide a flat torsional spring 5 for holding the rail 1 in supporting position. This spring fits tightly in slits (Fig. 5) in turned-down corners 7 of the rail 1. Midway of its length this spring 5 is also fixed in a slit 8 in the vertical arm 9 of an angular shaft 10 which floats in bearings 11, 12. The reduced end 13 of the vertical arm

55 9 engages a perforation in the rail 1, and when the arm 9 is truly vertical the rail 1 is held in matrix supporting position by reason of the fact that the spring 5 is at a right angle to the rail 1 throughout its length 60 although not under tension. As a means for retracting the rail 1 to non-supporting position, I provide a spring-lever 14 the inner end of which is capable of engaging a stud 9^a in the vertical arm 9 and thus forcing the arm 65 9 outward against the torsional force of the

spring 5. The spring-lever 14 is controlled by means of a handle 15 the upper end 16 of which is cam-shaped and therefore controls the movement of the spring-lever 14 and rail 1 to an in or out position according to the 70 position of the handle 15.

It may be noted that the spring-lever 14 is effective to move the rail 1 only when the rail is at its extreme right-hand position. This provision is made because of the presence of a hook 17 on the

75 rail 1, which clears the rail cap A only at the right-hand end thereof as in the common construction, and in order to permit the rail 1 to be retracted to nonoperative position; therefore any inadvertent movement of the

80 handle 15 when the rail 1 is advanced longitudinally to the left will be non-effective and the parts will not be subjected to strain or breakage by reason of the fact that the hook 17 is locked behind the rail cap A. It will

85 be seen that as mounted in the manner described the rail 1 is freely movable both longitudinally and laterally. In addition, I provide for an angular movement of this rail in order that its receiving end may be moved outwardly a selected and controlled distance to permit a predetermined group of matrices to drop therefrom to lower position. (See

90 Fig. 12.) This is accomplished by manually holding the left-hand end of the rail 1 in while moving the receiving end thereof out under control of the handle 15. A greater or less number of matrices will therefore be permitted to drop to lower position according to

95 the amount the rail is permitted to move as controlled at opposite ends. This arrangement displaces the usual bridge section of the duplex rail, which has the disadvantage that only and all the matrices resting thereon are

100 caused to drop when it is retracted, whereas it might be desired to drop more or fewer matrices than are supported on the usual bridge-section.

105 The rear duplex rail 2 is movable longitudinally in a groove 18 in a tumbler 19 mounted in a bore 20 in the back wall 21 of the assembler. This tumbler is movable axially by means of a finger-piece 22 operating in a slot 23 in the back wall 21. A pin 24 in the finger-piece 22 engages a spiral

110 groove 25 in a floating shaft 26 which is fixed to the slide 27 on which the supporting ledge 2 is formed. The shaft 26 is movable axially and longitudinally in a reduced continuation 115 20^a of the bore 20. By reason of this construction, movement of the finger-piece 22 to the right will cause the tumbler 19 to move to the position shown in Fig. 13, placing the rail in inoperative position; and movement of the

120 finger-piece to the left will render the rail operative as shown in Figs. 7, 13 and others. A semi-annular groove 28 in the floating shaft 26 is engaged by the end of an operating lever 29 entering through a slot 30 in

125 the rear wall 21. Movement of this lever by 130

the key-controlled means to be described causes the rear rail 2 to move longitudinally opposite and with the front rail 1. Like the front rail, this rear rail is provided with a 5 matrix-retaining hook 31. By reason of these hooks, movement of the rails to the left will insure that any matrices supported thereon will move therewith, thus retaining the matrices in raised position when the rails 10 move to the left to permit other matrices to be assembled in lower position. Otherwise stated, these hooks prevent the rails from being retracted to the left by means of the re- 15 tracting spring (39) except as permitted by the normal advance of the matrices in the assembler.

Longitudinal movement of the front duplex rail 1 is directly controlled by means of a lever 32 having an offset end 33 which engages the rail 1 and is free to turn in the lever 32, thus permitting of the lateral movement of the rail 1 under control of the handle 15. The lever 29 which controls the rear rail 2 clears through an opening 34 in the assembler floor 35, and both the rear 29 and front 32 controlling levers are secured to a rocker element 36 connected to the assembler by means of a hinge-pin 37. A spring 38 tends to keep the front 1 and rear 2 rails in 25 their right-hand or receiving position, but a stronger spring 39 overcomes such tendency when it is desired to retract the upper rails so as to permit the matrices to enter the assembler in their lower position. This 30 stronger spring 39 is the common assembling elevator counterbalancing spring, acting in usual manner upon the assembling elevator lever 40. A horizontal arm 41 of the rocker 35 is universally connected with a link 42 having its lower end bifurcated (42^a) and in engagement with a stud 43 projecting from the elevator lever 40. Since the link 42 is stopped against the stud 43, a downward movement of the lever 40 will permit the 40 weaker spring 38 to move the duplex rails to receiving position, and a return movement of the lever 40 will retract the rails longitudinally as permitted by the advance of the matrices X in the assembler, only a slight movement of the lever 40 being required to accomplish the desired result. In order that the lever 40 may be thus moved and held in a selected position, I provide instead of the usual link connection between the assembler floor 35 and lever 40, a compound connection 45 comprising a link 44 extending beyond the lever 40 and connected thereto by means of a return link 45. This indirect connection permits the link 44 to swing in an arc while 50 the assembler is at rest in lowered position, and when thus swung the lever 40 will rise and fall accordingly and move the duplex rails, through the connections described. When the counterbalancing spring 39 moves the lever 40 up as shown in dotted lines in

Fig. 4, the effect of such movement is to throw the link 44 to the rear in its arc of movement; therefore moving the link 44 forward will force the lever 40 down by swinging the intermediate link 45 forward at 50 its lower end; and since this movement is resisted by the spring 39, the parts must be latched in order to retain this position. For such purpose I provide an operating lever 46 centrally pivoted on the elevator lever 40 and connected by means of a link 47 to the end of the swinging link 44. The operating lever 46 carries a stop 48 which engages a notch 49 in a latching lever 50. The latching lever 50 is pivotally mounted on the aforementioned stud 43, and a spring 51 presses it upward against the latching stop 48. The forward end 52 of the latch 50 is shaped to serve as a finger key conveniently located relative to the keyboard Z and especially relative to the spacer key Y which is usually employed immediately before and after shifting the duplex rail. When this finger key is pressed down the stop 48 is freed from the notch 49 and through the train of connections described the duplex rails are retracted longitudinally but gradually as the matrices accumulate in the assembler against the usual assembler-slide finger 77. The assembled slide 79 is restored by means of a spring 80 or in any usual manner, and its restoring spring is sufficiently strong to overcome the effect of the rail-retracting spring 39, hence the rails are retracted only in time with the delivery of matrices to the lower or stationary rails 65, 65^a. An auxiliary spring 47^a (Fig. 4) may be employed to insure positive and full movement of the parts controlling the retraction of the rails. The releasing movement of the latching lever 46 is limited by contact of the stud 48 with the angular forward end 51^a of the spring 51, which projects through the lever 50 for this purpose. The spring 51 is under tension against the lever 40. The compound connection between the elevator and the lever 40 prevents the rear thrust and friction between the elevator and its guides when the elevator rises, hence is an improvement apart from its other function as described.

Since the duplex rail 1 must align with a rail 53 in the usual intermediate channel C through which the matrices are carried toward casting position, it is therefore necessary that the duplex rail 1 be in its right-hand position when the assembler approaches its elevated position; otherwise the assembler rail 1 would be stopped beneath the transfer rail 53 and the matrices could not move from the assembler. This necessity is provided for by the structure as described, as will be seen from a comparison of the drawings showing the assembler in raised and lowered position. If the assembler rail 1 is to the left when the assembler is elevated, the link 42 moves away 130

from the stud 43, and the spring 38 moves the duplex rails to the right before the assembler is fully elevated. This action will of course cause the operating lever 46 to move 5 toward latching position, but the movement thereof is not sufficient to cause the latch to function, hence the duplex rails will always return to or remain in their previously employed position when the assembler is lowered to normal position. The position of the duplex rails to the right when the assembler is raised has the effect of locking the matrices against displacement due to jar when the assembler is raised with excess force, the 10 matrices in lower position being locked in such position by reason of the fact that their lower lugs are beneath the duplex rails.

It is customary to provide a delivery channel alining piece 54 to insure the matrices 20 entering beneath the rail 53 when assembled in lower position with the duplex rail 1 retracted laterally, and the duplex rail ordinarily carries an operating part to raise this alining piece 54 when the duplex rail is operative, thus opening the channel above the rail 53. Since the usual operating element 25 is not adaptable to the longitudinally movable rail 1 I provide in lieu thereof an element 55 pivoted in the rail cap A and carrying a stud 56 which clears through an opening 57 and engages a slot 58 in the rail 1, this slot being of sufficient length to permit the requisite longitudinal movement of the rail 1; but when the rail 1 is moved in or out the operating element 55 is thereby caused to engage or 30 miss the alining piece accordingly, in manner similar to the usual construction.

The extent of movement of the duplex rail 1 under control of the spring 5 and handle 15 40 is limited by means of a boss strip 59 on the rail 1, this boss being accommodated in a recess 60 in the rail cap A and this recess being of appropriate width to permit of the necessary transverse movement of the rail 1 to and 45 from operative position.

In order that the features added to the assembler by this invention may not materially increase the manufacturing cost thereof, I 50 have eliminated a number of parts heretofore considered essential. Several of these eliminations are incidental to the manner of mounting and moving the rail 1. In addition I have simplified and generally improved the assembler gate as follows: The bearing shaft 61 and side arms 62 are made integral and continuous, thus providing a more rigid and dependable construction than heretofore employed. For convenience in assembling, this bearing shaft enters open bearings 63 and 55 is held in place by means of pins 64 concealed beneath a removable lower rail 65. The rail 65 projects beyond the assembler front wall at the left thereof, providing full support for the upper rail 1 when moved to the left as described. Midway of its length the gate shaft

61 is provided with a handle 66 which extends through an opening 67 in the assembler front wall B, in a position and at an angle convenient for use in opening and closing the gate. Instead of the usual return spring and mechanism at the left of the assembler I provide a simplified construction employing only a wire spring 81 (Fig. 14) and anchoring block 68 therefor. At its opposite ends this spring bears in holes 69 and is bent a proper amount to exert sufficient pressure to hold the gate normally closed. The construction is such that the "feel" of the gate as it is opened or closed is the same as heretofore and that to which operators have become accustomed; and the unequal strain exerted at opposite ends of the gate by reason of the old construction, and a tendency to wear away certain parts and leave the gate loose, have been eliminated by my improved construction, and the handle for the gate is an added feature. The gate rail 70 is secured to return bends 71 from the side arms 62, and a line centering scale 72 (Fig. 2) similar to that described in my U. S. Patent No. 1,310,487, 85 may be hung on a rod 73 resting in the facing ends of the return bends 71. In normal position the side arms 62 are stopped against the projecting ends of the lower rail 65 and there held by the spring 81.

The lower rail 65 is held in place by means of screws 74 and may be renewed from time to time as wear occurs at its receiving end. The usual intermediate channel wall D is recessed as at 75 to accommodate the extensions of the lower and upper assembler rails.

As before stated, the use and operation of my invention takes into consideration the spring-restored assembler slide 76 and finger 77. Assuming that the first matrix in a line is assembled on the upper rails 1, 2, then a shift back to the lower rails will ensue by depressing the latch 50; but in such case the rail hooks 17, 31 will be in front or to the right of the last matrix assembled in upper position, hence the duplex rails will retreat to the left gradually as permitted by the advance of the assembler finger 77 as matrices are assembled on the lower rails, the raised matrices moving with the rails so far as the 110 rails move to the left. As a result, the space between the star wheel 78 and the assembler slide finger 77 is always filled with matrices and spacers, which is of importance since otherwise the matrices would be liable to fall from the supporting rails and scatter at large. When the rails are again shifted to the right the continuously-revolving star-wheel 78 jogs the matrices and as a result movement of the upper rails is not resisted by reason of the weight of the matrices thereon, and the spring 38 will quickly move the rails to receiving position when the operating lever 46 is pressed to latching position. Usually a spaceband 79 intervenes between 115

the last matrix supported on the upper rails and the first matrix assembled in lower position, and this prevents the first incoming matrix of a group thereof destined for the 5 lower position from lodging on the rail hook 17, 31.

Having thus described the advantages, construction and mode of operation of my invention, what I claim as new is:

- 10 1. In an assembler for typographical elements, the combination with upper and lower supporting rails for said elements of means for moving the upper supporting rail longitudinally to a position for receiving said 15 elements, means for locking said rail in its receiving position, means for releasing it from its receiving position, and means for causing it to be retracted longitudinally in time with the accumulation of said typographical elements 20 on said lower rail.
2. A combination as specified in claim 1, including also means whereby said upper rail may be retracted laterally to non-use position.
- 25 3. In combination, an assembler for typographical elements having upper and lower rails for supporting said elements, means for advancing said upper rail to a position for receiving and supporting selected typographical elements, means for holding it in 30 its advanced position, and means for causing it to be retracted longitudinally as permitted by the advance of the line of typographical elements incident to the assembly thereof on 35 said lower rail.
4. A combination as specified in claim 3, including also means for retracting said upper rail laterally to inoperative position and means for locking it in inoperative position.
- 40 5. In an assembling elevator for typographical elements, an upper supporting rail for said elements, means for moving said rail longitudinally to receive or reject said elements, selectively, and means for causing said rail to move from rejecting to receiving position incident to the raising of said elevator from assembling positions and to return to rejecting position incident to the return of said elevator to assembling position.
- 50 6. In an assembler for typographical elements having upper and lower rails for supporting said elements at upper or lower levels, selectively, key-controlled means for causing said upper rail to move to supporting or rejecting position, selectively, said means causing said rail to move to rejecting position in time with the accumulation of the typographical elements in the assembler.
- 60 7. In an assembler for typographical elements, an upper supporting rail movable longitudinally to receive or reject said elements, selectively, when in use, and movable axially to non-interfering position when not in use.
8. In an assembling elevator for typographical elements, an upper rail therein for supporting or rejecting said elements, selectively, a lever for raising said elevator from assembling position, and means controlled by the action of said lever for causing said upper rail to move to a position serving to lock said elements against displacement incident to the raising of said elevator from assembling position.
9. In an assembling elevator for typographical elements, an upper rail therein movable to a position for receiving or rejecting said elements, selectively, means for locking said rail in a selected position, means for raising said elevator, and associated means for causing said rail to either move to or maintain its receiving position when said elevator is raised, according to the position selected for said rail when said elevator is in assembling position.
10. In an assembler for typographical elements having upper and lower rails for supporting said elements at upper or lower levels, selectively, according to the operative or non-operative position of the upper rail, means comprising a torsional spring for causing said upper rail to move to and maintain operative position, and manual means for retracting said rail and locking it in non-operative position.
11. In an assembler for typographical elements having upper and lower rails for supporting said elements at upper or lower levels, selectively, means for moving the upper one of said rails to or from operative position an equal amount throughout its length, and also permitting moving said rail angularly throughout its length in order that a selected group of typographical elements at the receiving end thereof may be permitted to drop to the lower one of said rails.
12. In an assembler for typographical elements having therein an upper rail for supporting selected elements at an upper level, means for moving said rail longitudinally to support or reject said elements, selectively, when said rail is in operative position, and means for moving said rail laterally to non-operative position from receiving position, said latter means being non-effective when said rail is in rejecting operative position.
13. In an assembler for typographical elements having a gate for retaining said elements and movable outwardly to provide access thereto, a central spring capable of exerting uniform pressure throughout the length of said gate and tending to retain it in normal position, and a central handle extending from the pivotal axis of said gate, whereby said gate may be moved outwardly against the tension of said spring without placing unequal strains on said gate.
14. In an assembler for typographical elements having a gate movable to and from nor-

graphical elements, an upper rail therein for 65 supporting or rejecting said elements, selectively, a lever for raising said elevator from assembling position, and means controlled by the action of said lever for causing said upper rail to move to a position serving to lock said 70 elements against displacement incident to the raising of said elevator from assembling position.

9. In an assembling elevator for typographical elements, an upper rail therein 75 movable to a position for receiving or rejecting said elements, selectively, means for locking said rail in a selected position, means for raising said elevator, and associated means for causing said rail to either move to or 80 maintain its receiving position when said elevator is raised, according to the position selected for said rail when said elevator is in assembling position.

10. In an assembler for typographical elements having upper and lower rails for supporting said elements at upper or lower levels, selectively, according to the operative or non-operative position of the upper rail, means comprising a torsional spring for causing 90 said upper rail to move to and maintain operative position, and manual means for retracting said rail and locking it in non-operative position.

11. In an assembler for typographical elements having upper and lower rails for supporting said elements at upper or lower levels, selectively, means for moving the upper one of said rails to or from operative position 95 an equal amount throughout its length, and also permitting moving said rail angularly throughout its length in order that a selected group of typographical elements at the receiving end thereof may be permitted to drop to the lower one of said rails.

12. In an assembler for typographical elements having therein an upper rail for supporting selected elements at an upper level, means for moving said rail longitudinally to support or reject said elements, selectively, 110 when said rail is in operative position, and means for moving said rail laterally to non-operative position from receiving position, said latter means being non-effective when said rail is in rejecting operative position.

13. In an assembler for typographical elements having a gate for retaining said elements and movable outwardly to provide access thereto, a central spring capable of exerting uniform pressure throughout the length 115 of said gate and tending to retain it in normal position, and a central handle extending from the pivotal axis of said gate, whereby said gate may be moved outwardly against the tension of said spring without placing unequal strains on said gate.

14. In an assembler for typographical elements having a gate movable to and from nor-

mal position, a central handle extending from the pivotal axis of said gate, whereby said gate may be opened and closed without placing unequal strains thereon.

5 15. In an assembler for typographical elements having a gate movable to and from closed position, a spring associated with the pivotal axis of said gate and secured thereto, whereby the strain exerted by said spring 10 to close said gate will be equal at opposite ends of said gate.

16. In a typographical machine, an assembling elevator for typographical elements provided with an upper rail movable to support 15 or reject said elements at an upper level, selectively, a keyboard for controlling the release of said elements into said assembler, key means adjacent to said keyboard for controlling the movement of said upper rail to and 20 from rejecting or supporting position, selectively, when said elevator is in assembling position, and an interconnection between said key means and said upper rail and movable with said elevator for the purpose of controlling the position of said rail when said elevator is in elevated position.

17. In an assembling elevator for typographical elements, a lever for raising said elevator, a link extending from said elevator 30 to a point below the swinging end of said lever, and an intermediate link connected at said point and extending upward therefrom to a connection with said lever, whereby said

elevator will be balanced while being raised by means of said lever.

35 18. In a typographical assembler, an upper matrix supporting rail movable longitudinally to support or reject matrices, selectively, key means for predetermining the position of said rail, a spring for causing said rail to move to supporting position, the spring-restored assembler slide and finger movable according to and by reason of the accumulation of matrices in the assembler, and a spring for causing said rail to move to 40 non-supporting position in time with the movement in a similar direction of said assembler slide and finger following the actuation of said key means for predetermining such movement of said rail.

45 19. In a typographical assembler having a duplex rail movable for receiving or rejecting typographical elements, selectively, a key for causing the receiving movement of said rail, a separate key for causing the rejecting movement thereof, and means whereby the actuation of one of said keys for causing the movement of said rail in one direction will automatically set the other one thereof in a position in which its release therefrom will cause 50 the movement of said rail in an opposite direction.

55 Signed at Los Angeles, Los Angeles county, California, this 19th day of October, 1927.

60 GEORGE E. MARLATT.
